UNITED STATES PATENT OFFICE.

EDMUND N. BROWN AND MILTON H. SHOENBERG, OF SAN FRANCISCO, CALIFORNIA.

GUARD FOR HEATERS.

1,368,108.

Specification of Letters Patent.

Patented Feb. 8, 1921.

Application filed October 1, 1919. Serial No. 327,762.

To all whom it may concern:

Be it known that we, EDMUND N. BROWN and MILTON H. SHOENBERG, citizens of the United States, and residents of the city and county of San Francisco, State of California, have made a new and useful Invention—to wit, Improvements in Guards for Heaters—of which the following is a specification.

10 Our invention has for its object the protection of persons and adjacent objects from the heated portion of an electric heater, as for example from the heated element which in practice is usually sufficiently hot to 15 cause inflammable objects coming in contact therewith to take fire.

The form and method of attaching the said guard wires and parts of the heater form the basis of our invention. Heretofore it has been customary to attach guard wires by grooves, hinges, or welding, or in some other well known manner, and to the heat reflecting surface; whereas, in our present invention we assemble the wires 25 forming the cage on a spring ring which normally is expanded in the form of a circle. By springing together the two sides of the ring the circle diameter is reduced and said ring is then slipped under a flange 30 or circular tongue, preferably formed with the reflector, or the protector flange extending beyond the reflector. The spring action of the ring when released holds the protecting cage in place.

35 Referring to the drawings:

Figure 1 is a front view of the assembled cage with the retaining flange of the heater shown in dotted lines.

Fig. 2 is a side view of the cage with the 40 reflector and its protecting flange, and a retaining tongue or groove, shown in dotted lines.

Fig. 3 is an assembled perspective view of 45 an electric heater with our guard wire cage in assembled position.

Throughout the figures like numerals refer to similar parts.

The wires of the guard frame or cage are indicated as by 1, 6, 7, and these are assembled in a frame of substantially circular section as indicated at 2. The frame and its wires are assembled with the heater, preferably against the flange 3, and within the annular recess 4 formed by the overhanging flange 5. The frame 2 is made

preferably of spring material such that by pressing together the wires 6, 7, in the direction of the arrows in Fig. 1, the space between the ends of the frame or gap in the frame structure, as shown at 8, is closed, 60 thereby reducing the periphery and consequently the diameter of the frame 2, so that it will pass within the recess or space 4. Upon releasing the pressure against the wires 6 and 7, the frame springs outwardly 65 into the space 4 and is then engaged in retained position under the flange or tongue 5. The guard on the heater then having the appearance as indicated in Fig. 3, the heat generating element 12 is protected with 70 in the reflector 9 on the one side and the cage as 1, 6 and 7 on the opposite side. We prefer to assemble the wires as 1, 6 and 7 where they converge as by the ring 10 and plate 11, this gives rigidity to the structure 75 so as to better maintain the spring relationship of the parts and also gives a neat finish to the assembled structure.

We claim:

1. In a heater, a heat element constructed 80 and adapted to radiate heat and mounted substantially at the focus of a concave heat reflector, and a reflector and an annular flange disposed at the periphery of the reflector and having an annular recess adapted 85 to engage a ring, in combination with a ring to which are fixed a plurality of guard wires, said ring having a cut in its periphery to allow of distortion and said ring engageable with said recess. 90

2. In combination with an electric heater, a guard frame consisting of a center member to which are attached a plurality of radiating guard wires, said guard wires attached at their outer extremities to a ring, 95 said ring parted at its periphery for the purpose of permitting lateral displacement whereby it may be engaged within a flanged recess, and a heat radiating reflector having a peripheral flange, said flange provided 100 with said recess.

3. In combination with an electric heater, a guard frame consisting of a center member to which are attached a plurality of radiating guard wires, said guard wires attached at their outer extremities to a ring, 105 said ring parted at its periphery for the purpose of permitting displacement whereby it may be engaged within a flanged recess, and a heat radiating reflector having a 110

peripheral flange provided with said recess, said guard wires being formed substantially as on the surface of a sphere.

4. In combination with an electric heater, a guard frame consisting of a center to which are attached a plurality of radiating guard wires, said guard wires attached at their outer extremities to a ring, said ring parted at its periphery for the purpose of permitting lateral displacement whereby it may be engaged within a flanged recess, and a heat radiating reflector having a peripheral flange formed with said recess, and a heat radiating element mounted between said guard wires and said reflector.
5. In combination with an electric heater, a guard frame consisting of a center mem-

ber to which are attached a plurality of radiating guard wires, said guard wires attached at their outer extremities to a ring, 20 said ring parted at its periphery for the purpose of permitting lateral displacement whereby it may be engaged within a flanged recess, a heat radiating reflector having a peripheral flange with said recess, said 25 guard wires being formed substantially as on the surface of a sphere, and a heat radiating element mounted between said guard wires and said reflector.

In testimony whereof, we have hereunto set our hands at San Francisco, California, this 22nd day of September, 1919.

EDMUND N. BROWN.
MILTON H. SHOENBERG.
